(57) **CLAIM**

The ornamental design for a worksurface assembly, as shown and described.

DESCRIPTION

In a preferred embodiment, the nature of this product is a worksurface assembly that is part of a modular office furniture system.

FIG. 1 is a top, front, left perspective view of a first embodiment of a worksurface assembly embodying our new design; FIG. 2 is a front elevational view thereof;

FIG. 3 is a left side elevational view thereof;

FIG. 4 is a right side elevational view thereof;

FIG. 5 is a top plan view thereof;

FIG. 6 is a rear elevational view thereof;

FIG. 7 is a bottom plan view thereof;

FIG. 8 is a top, front, right perspective view of a second embodiment of a worksurface assembly embodying our new design, the right side elevational view being identical to the view of FIG. 4, the left side elevational view being identical to the view of FIG. 3, the top plan view being a mirror image of the view of FIG. 5, the rear elevational view being identical to the view of FIG. 6, the bottom view being a mirror image of the view of FIG. 7, the front elevational view being a mirror image of the view of FIG. 2;

FIG. 9 is a top, front, left perspective view of a third embodiment of a worksurface assembly embodying our new design, the top plan being identical to the view of FIG. 5; the rear elevational being identical to the view of FIG. 17, the bottom view being identical to the view of FIG. 7;

FIG. 10 is a front elevational view thereof;

FIG. 11 is a left side elevational view thereof;

FIG. 12 is a right side elevational view thereof;

FIG. 13 is a top, front, right perspective view of an fourth embodiment of a worksurface assembly embodying our new design, the right side elevational view being identical to the view of FIG. 12, the left side elevational view being identical to the view of FIG. 11, the top plan view being a mirror image of the view of FIG. 5, the rear elevational view being identical to the view of FIG. 17, the bottom view being a mirror image of the view of FIG. 7, the front elevational view being a mirror image of the view of FIG. 10;

FIG. 14 is a top, front, left perspective view of a fifth embodiment of a worksurface assembly embodying our new design;

FIG. 15 is a left side elevational view thereof;

FIG. 16 is a front elevational view thereof;

FIG. 17 is a rear elevational view thereof;

FIG. 18 is a right side elevational view thereof;

FIG. 19 is a top plan view thereof; and,

FIG. 20 is a bottom plan view thereof.

The broken line representations of worksurface structure in FIGS. 1, 3, 4, 5, 7, 8, 9, 11, 12, 13, 14, 15, 18, 19 and 20, of vertical panel structure in FIGS. 2, 3, 4, 6, 7, 10, 11, 12, 15, 16, 17, 18 and 20, of worksurface seams in FIGS. 1, 5, 8, 9, and 13, of shelf structure in FIGS. 1, 7, 8, 9, 10, 13, 14, and 20, and of vertical worksurface supports in FIGS. 1, 2, 3, 4, 7, 8, 9, 10, 11, 12, 13, 14, 15, 16, 18, and 20, form no part of the claimed design.
